United States Patent Office.

J. DUTTON STEELE, OF POTTS TOWN, PENNSYLVANIA.

Letters Patent No. 63,666; dated April 9, 1867.

IMPROVEMENT IN BRIDGES.

The Schedule referred to in these Letters Patent and making part of the same.

TO ALL WHOM IT MAY CONCERN:

Be it known that I, J. DUTTON STEELE, of Pottstown, in the county of Montgomery, and State of Pennsylvania, have invented a new and improved Mode of Building Truss Bridges; and I do hereby declare that the following is a full and exact description thereof, reference being had to the accompanying drawing, and to the letters of reference thereon.

The nature of my invention consists in so arranging the braces and counter-braces of truss bridges as to dispense with the use of vertical posts and binding-rods between the cords, and in causing the braces and counter-braces to act as posts and binding-rods, by which means all the angles of thrust upon the cords are made equal, the absolute strain upon any one set of braces or counter-braces is reduced one-half, perfect bearing for all the braces and counter-braces is obtained during the elasticity which is caused by a moving load, and the full action of the counter-braces in transferring the strain from one set of braces to another is secured. As a consequence of these results the amount of material in either series of braces may be reduced one-half, and as the truss is about as well adapted to resist upwards as downward strain, and the power to resist upward strain being a corrective of the tendency to undulate under moving loads, it is unusually stiff and all its material is in useful action.

To enable others skilled in the art of bridge building to make use of my invention I will proceed to describe its construction.

The cords may be either of wood or iron, in the usual mode, to connect which I employ a series of strut main braces, *a a**, and a series of brace-rods, *b b*, also a series of strut counter-braces, *d d*, either of wood or iron, and a series of counter-brace rods, *c c*, thus making a double series of diagonal braces, both main and counter, so arranged that the whole not only act as braces, but also perform the functions for which vertical posts and binding rods are usually employed. The strut counter-braces may be entirely dispensed with in bridges for ordinary travel, and a portion of them may be left out in railroad bridges, without impairing the stability of the structure, or they may be retained and a portion of the counter-brace rods may be dispensed with as circumstances may dictate.

I do not claim as my invention the use either of a series of main and counter-braces, in combination with vertical posts and vertical binding-rods, nor a series of main and counter-brace rods in connection with vertical posts and vertical binding-rods, or their equivalents, but I do claim as my invention—

The combination of the two series, substantially as set forth, or their equivalents, made either of wood or of iron, in the manner and for the purpose hereinbefore described.

J. DUTTON STEELE.
